UNITED STATES PATENT OFFICE.

AMOS E. BROWN, OF DAMASCUS, ARKANSAS.

TRAIN-CONTROLLED RAILWAY-CROSSING GATE.

Application filed August 26, 1926. Serial No. 131,737.

The invention relates to gates for protecting railway crossings by highways and has for its object the provision of means for actuating a stop gate at railway crossings that is actuated into a closed position by mechanism operated by an electric motor, the motor being controlled by a train approaching the crossing from either side thereof and holding the gate closed until the train leaves the section of the track connected with the motor, a counter-balance weight being secured to the gate and normally tending to open the gate when the motor ceases to operate.

The invention will be described in detail hereinafter and will be found illustrated in the accompanying drawings, in which

Figure 1 is a plan view of a railway and highway crossing showing one of my gates located for controlling the crossing,

Figure 2 is a vertical sectional view of the gate stand, showing the gate in position and the operation mechanism therefor, and including a diagram of the electric circuit for controlling the operation of the motor,

Figure 3 is a fragmental sectional view on a plane indicated by the line 3—3 of Figure 2,

Figure 4 a detail view in section of the gate shaft actuating mechanism showing the position of the parts when the gate is in an open position,

Figure 5 is a similar view as that of Figure 4 showing the position of the parts when the gate is in a closed position, and

Figure 6 is a transverse sectional view on a plane indicated by the line 6—6 of Figure 4.

In the drawings similar reference characters will be used to designate corresponding parts throughout the several views.

In Figure 1 is shown a railway crossing in which A indicates the vehicle highway and B the railroad track, the gate for protecting the highway A being operated from a gate stand, the gate being designated 2.

Within the gate stand 1 is a supporting frame 3 from which the various instruments hereinafter described to operate the gate 2 are supported, 4 designating a shaft journaled in said frame 3 on which the gate 2 is secured for rotation therewith, and held normally in a raised or open position by means of a weight 5 that is sufficiently heavier than the gate to raise the gate and rotate

the shaft 4 and operate the working parts connected therewith that will be hereinafter more fully described, when the power for closing the gate is shut off.

A motor 6 is supported in the upper part of the frame 3 and controlled by means of the wires 7 and 8 connected with a section of the track B, designated 9 that is insulated from the remainder of the track the distance on each side of the highway A as shown at 10, 11 indicating a source of electric energy to actuate the motor 6. It will be apparent from this construction that when a train enters the section 9 of the track B that the circuit will be closed by the wheel trucks of the train to energize the motor 6, and the energization of the motor will continue as long as a part of the train remains on the section 9.

A series of shafts 12, 13, 14, and 15 are journaled in frame 3. Shaft 12 is geared to the shaft 16 of the motor 6 by the gearing 17, shafts 12 and 13 are connected by gearing 18, shafts 13 and 14 are connected by gearing 19, and shafts 14 and 15 are connected by gearing 20, each of these sets of gearing being arranged to reduce the speed of the motor shaft 16 to a desired speed of the shaft 15. 21 indicates a vertical shaft 85 journaled in a supporting member 22 secured in the supporting frame 3 and geared to shaft 15 by the bevel gearing 23. 24 indicates a ratchet wheel secured to shaft 21. 25 designates a shaft having a hollow head 90

26 to receive the end of the shaft 21 and the ratchet wheel 24, and is held from endwise movement relatively to the shaft 21 by means of a cover plate 27. 28 indicates a pawl pivotally mounted as at 29 in the head 26 95 and held in engagement with the teeth of the ratchet wheel 24 by means of an expandable coil spring 30. The shaft 25 is formed with a worm or threads 31. 32 indicates a slide bearing supported by member 33, and forming a bearing for the plunger 34 that is hollow and internally threaded as shown at 35 to engage the threads 31 on the shaft 25. Stem 36 of the plunger 34 extends through an opening 37 in the bottom of the slide bearing 32 and has a cross head 38 to

which is pivotally secured links 39 at one of their ends, the other ends of said links 39 being pivotally secured to a disk 40 secured to shaft 4. 100

41 indicates a bell or any other suitable alarm that is energized from the circuit 105

comprising the wires 7 and 8 by means of the wires 41 and 42, it being designed that the bell or other alarm 41 shall be energized and sound an alarm simultaneously with the operation of the gate.

In operation it will be apparent that when the train enters the section 9 of the track, as heretofore referred to and the motor 6 is energized, that shaft 21 will be actuated through the train of gearing comprising the shafts 12, 13, 14, and 15, and the gearing 17, 18, 19 and 20, and the gearing 23. When the shaft 21 is actuated the plunger 34 will be moved downwardly through the threaded engagement with the threads or worm 31 and the threads 35, and by such movement downwardly the shaft 4 will be rotated to move the gate 2 into a closed position; the position of the plunger 34 when the gate is closed being shown in Figure 5 of the drawings, and the continued operation of the motor 6 will serve to hold the plunger 34 in a lowered position after the threads 31 and 35 are disconnected, the shaft 25 being turned on the upper end of the plunger 34 and the gate will be held in a closed position as long as any part of a train is on the section 9 of the track. When the train has entirely left the track the energization of the motor will cease and the weight 5 will then move the gate to its open position and by so doing the plunger 34 will be raised on the shaft 25, and the parts will be restored to the original position ready for another operation.

44 indicates a spring in the slide bearing 32 and engaging the plunger 34 and normally tending to raise the plunger, said spring assisting in return of the plunger to its original position after operating the gate to a closed position as hereinbefore described.

The invention has been shown connected with but a single gate on one side of a railway at a crossing, but it will be clearly understood that a gate is to be erected at each side of the crossing and that either the two gates may be operated by the well known means for actuating railway gates from a single control, or a separate operating mechanism may be provided for each gate.

What is claimed is:—

1. A crossing gate operating mechanism, comprising a stand, a shaft journaled therein, a gate secured to said shaft, a disk secured to the shaft, an electric motor supported in the stand and controlled by a train, an internally threaded plunger, a stem on said plunger, a link connecting said stem and disk, a threaded shaft engaging in said plunger, said shaft being geared to said motor to actuate the gate to closed position, and a counter-weight to return the gate to open position when the motor is stopped.

2. A railway crossing gate operating mechanism, comprising a stand, a shaft journaled in said stand, a gate secured to said shaft, a counter-balance weight secured to the gate and operating to hold it normally in open position, a slide bearing in said stand, an internally threaded hollow plunger in said slide bearing and operatively connected to said shaft to rotate it, a shaft journaled in said stand and threaded to engage the internally threaded plunger, an electric motor supported in said stand, and gearing connecting said motor and the last mentioned shaft.

3. A railway crossing gate operating mechanism, comprising a stand, a shaft journaled in said stand, a gate secured to said shaft, a counter-balance weight secured to the gate and operating to hold it normally in open position, a vertically arranged slide bearing in said stand, an internally threaded hollow plunger in said slide bearing and operatively connected to said shaft to rotate it, an expandable spring in said slide bearing and engaging said plunger to normally raise it, a vertical shaft journaled in said stand and having a ratchet wheel secured thereto, a threaded shaft working in the internally threaded plunger, a detent on said shaft and engaging the ratchet wheel aforesaid, an electric motor supported in said stand, means operated by a train to control the operation of the motor, and gearing connecting said motor and the vertical shaft.

In testimony whereof I affix my signature.

AMOS E. BROWN.
